UNITED STATES PATENT OFFICE.

HARRY W. JONES, OF NEW YORK, N. Y., ASSIGNOR TO AMERICAN CAN COMPANY, OF NEW YORK, N. Y., A CORPORATION OF NEW JERSEY.

SIFTER TOP.

Application filed June 12, 1920. Serial No. 388,535.

To all whom it may concern:

Be it known that I, HARRY W. JONES, a citizen of the United States, residing in New York, in the county of New York and 5 State of New York, have invented a new and useful Improvement in Sifter Tops, of which the following is a specification.

This invention relates in general to sifter top cans and has for its object broadly the 10 provision of new and improved construction in cans having tops of this character wherein the sifter openings are provided by the manipulation by the user of the material of the can and without providing any separate 15 member or members for the closing of the perforation or sifter openings.

A principal object of the present invention is the provision of a construction in which the sifter openings will be tightly 20 closed when the can is received by the user and which will permit of the establishment of sifting conditions by the user and through the exertion of a lightly applied pressure to the can wall or end. The invention con- 25 templates in this respect a construction wherein the sifter openings may be provided by the user through and as a result of pressure exerted by his hand upon an appropriate portion of the can end.

Another principal object of the invention 30 is the manner in which the cuts are made in the metal walls of the can and again closed, so that finely powdered material will not sift through during transportation and handling. This is accomplished by first 35 making a dome top or profile (the profile may be of any configuration) of larger area than is actually desired, then slitting the metal to eventually where the sifter open- 40 ings will appear and then through a compres- sion of the dome surface by die action the dome area is reduced somewhat, so that the cut edges of the openings will be tightly 45 pressed together. In cutting metal in this manner more or less stretch occurs and it is very difficult to slit metal in this manner and push the parts back into their normal position and have the cut edges in close 50 enough contact, so that finely divided material would not sift through. But by the

tight that finely powdered material will not 55 sift through.

Another important object of the invention is the provision of a disintegrator extending inwardly of the can from the sifter end.

Another important object of the invention 60 is the provision of a can having these and other advantages which will not require the provision of additional parts or additional materials and which will be cheap to manu- 65 facture and of distinctive and pleasing appearance.

Numerous other objects and advantages 70 of the invention will be apparent from the following description taken in connection with the accompanying drawing which illus- 75 trates a preferred embodiment thereof.

Referring to the drawings:

Fig. 1 is a top plan view of a can embodying my invention;

Fig. 2 is a transverse vertical sectional 75 view through the same;

Fig. 3 is a perspective view of the top.

For the purpose of illustrating my invention I have indicated on the drawing a can body 10 of any preferred form and material 80 and a sheet metal end 11 suitably seamed thereto. In the present instance I provide an outwardly extending dome portion as indicated at 12 in Fig. 2. Lines of sever- 85 ance 13 are provided to set off lips or parts 14 disposed about the edge of the dome 12 and extending in toward a common center, i. e., the center of the dome.

The lines of severance 13 are formed by 90 cutting through the material. This cutting action or operation tends to press inwardly the dome and produce openings extending about the edges of the lips. After the cutting is accomplished the central part of the dome is pressed into position leaving merely 95 lines extending about the lips.

The central part of the dome is adapted 100 to be pressed in by pressure exerted by the thumbs of the user to produce separation on the lines of cut, thereby providing sifter openings and without the need of employing a pointed tool or implement as has frequently been required in connection with the use of structures usually provided prior to my present invention, such structures having 105 lips set off by scored lines, said lips being capable of being broken away about their edges and bent into the can by pressure

exerted by a punching tool or pointed implement.

In a can embodying my present invention the central part of the dome may be pressed inwardly and will receive a permanent inward set providing the openings as mentioned for sifting and providing also for the disintegration or breaking up of lumps within the contents of the can.

10 It is thought that the invention and many of its attendant advantages will be understood from the foregoing without further description, and it will be apparent that various changes may be made in the form, 15 construction and arrangement of the parts without departing from the spirit and scope of the invention or sacrificing all of its material advantages, the form hereinbefore being merely a preferred embodiment thereof.

20 I claim:

1. A can wall having lines cut through it and the parts of said wall being left in position to substantially close the can, the material of said wall at one side of said lines being capable of being pressed inwardly of the can to provide widened spaces forming sifter openings.

2. A can wall having lines cut through it and the parts of said wall being left in position to substantially close the can, the material of said wall at one side of said lines being capable of being pressed inwardly of the can to provide presented disintegrator edges for breaking up lumps of material within the can.

3. A can wall having integral portions partly severed and separable from the body of the wall when the body of the wall is pressed inwardly, and having other intermediate portions adapted to yield to said bending but which remain integral with and across the sifter top.

4. A can wall having sifter openings formed by cutting and partly separating portions of the material of the wall, said openings being closable after cutting by pressing the material of the wall to its original location, and said openings being opened by pressing the wall inwardly of the can and relatively to the partly severed portions.

5. A can wall having curved severed lines arranged about a central part said central part being capable of being pressed inwardly of the can, while maintaining its central position, to provide openings at said lines of cut.

6. A can wall having curved severed lines arranged about a central part said central part being capable of being pressed inwardly of the can, while maintaining its

central position, to provide openings at said severed lines.

7. A can wall having lips set off by severed lines and arranged in a circle, the material of the wall within the circle and between the lips being capable of being depressed to provide sifter openings at said severed lines.

8. A can wall having lips set off by severed lines and arranged in a circle, the material of the wall within the circle and said lips being normally pressed outwardly of the can and said material between said lips and within said circle being capable of being pressed inwardly of the can to provide sifter 75 openings.

9. A can wall having an outwardly protruding dome portion provided with severed lines, the central part of said dome portion being capable of being pressed inwardly to 80 provide sifter openings on said severed lines.

10. A can wall consisting of two portions held within the same plane by a plurality of contacting elements, one portion being adapted to be moved from the plane whereby 85 the contacting elements separate from one another to provide sifter openings between each two contacting elements.

11. A can wall having a stationary outer portion and a compressible inner portion, the connection between said outer portion and said inner portion being integral with a series of attaching elements adapted to separate at their abutting edges upon movement of the inner compressible portion.

12. A can wall having a stationary outer portion and a compressible inner portion, the connection between said outer portion and said inner portion being integral with a series of attaching elements adapted to separate at their abutting edges upon movement of the inner compressible portion, and to provide thereby a plurality of sifter openings.

13. A can wall comprising contiguous elements disposed within the same plane, the innermost element having a capability of movement relative to said plane, an intermediate element surrounding the innermost element and connected therewith and consisting of a series of adjacent abutting parts, also connected with an outer element, the adjacent parts of the intermediate element separating from each other upon the movement of the innermost element from the initial plane, and providing openings which are enlarged in direct proportion to the distance the innermost element is moved from the plane.

HARRY W. JONES.
